UNITED STATES PATENT OFFICE.

GEORGE H. BARSCHOW, OF TOLEDO, OHIO, ASSIGNOR TO THE AMERICAN METAL WHEEL & TOY CO., OF TOLEDO, OHIO.

STEERING-GEAR FOR CHILDREN'S PEDALED VEHICLES.

No. 802,548.

Specification of Letters Patent.

Patented Oct. 24, 1905.

Application filed September 26, 1904. Serial No. 225,924.

To all whom it may concern:

Be it known that I, GEORGE H. BARSCHOW, a citizen of the United States, residing at Toledo, in the county of Lucas and State of Ohio, have 5 invented a new and useful Improvement in Steering-Gear for Children's Pedaled Vehicles, of which the following is a specification.

My invention relates to steering-gear for children's pedaled vehicles, and has for its object to provide a simple, durable, inexpensive, and efficient mechanism for the purpose that is readily and conveniently operated by a child. I accomplish these objects by constructing a steering-gear adapted to be attached to the 15 body and running-gear of a child's pedaled vehicle, as hereinafter described, and illustrated in the drawings, in which—

Figure 1 is a perspective side view of my invention, and Fig. 2 is a similar front view 20 of the same. Fig. 3 is a perspective view of my invention attached to a body.

In the drawings, 1 is a front axle of a vehicle, upon which is mounted a truss-bolster 2, formed of the truss-straps 3, the connecting- 25 strap 4, angled U shape, and the bridge-bar 5. The truss-straps 3 each have outer and inner end portions 6 and 7 of unequal length, bent parallel with each other, and at equal distances from their free ends these end portions have 30 transverse orifices 8 in alinement, by which the bars 3 are mounted on the axle. The legs of the U-shaped strap 4 embrace and are riveted to the outer sides of the end portions 7, the legs being provided with orifices registering with the axle-orifices 8 of the end portions 7. The bridge-bar 5 is disposed over the U-shaped strap with its end portions resting and riveted to the top sides of the strap-bars 3, which slope downward therefrom to the end 40 portions 6 of the bars 3, the end portions 7 of the bars 3, the U-shaped strap 4, and the bridge-bar 5, forming, as connected, a central rectangular frame from which the truss-straps 3 extend in opposite directions to their end portions 6, which form shoulders at the inner ends of the journal portions 1^a of the axle 1.

The bridge-bar 5 has its central portion widened in disk form to provide a bearing 9, central of which and rigidly secured thereto 45 is the king-pin 10, by which the bolster 2 of the axle 1 is pivoted to the inverted tripod 11, which supports the front end of the body of the vehicle. The tripod 11 is composed of the strap-bar 12, having the legs 13 equally

angled outwardly from a central bearing portion 14, which is provided with a central orifice to receive the king-pin 10, and the leg 15, angled from a bearing portion 16, having a central orifice adapting it to be mounted on the pin 10 over the bearing portion 14, midway 55 between the legs 13, with the leg 15 extending upward and rearward at the same angle as the legs 13. The free end of the pin 10 has a suitable rivet-head formed thereon, by which the truss-bolster is prevented from becoming detached from the tripod. The legs 13 and 15 have their upper end portions angled outward in the same plane parallel with the plane of their bearing portions to form the feet 17, each perforated for the attachment 60 of the tripod by screws to the bottom of a vehicle-body. (Not shown.)

To the truss-straps 3 of the bolster 2 are pivoted the link-bars 18, one near each end of the bridge-bar 5, which extend rearward 65 and slightly inclined downward a suitable distance, and at their rear ends the link bars or rods are pivoted to opposite ends of a connecting-bar 19, and central between the pivoted attachments of the link-bars the bar 19 70 is provided with a fixed stem or rod 20, which extends upward a suitable distance through and above the body-base at a suitable rearward inclination, and upon the upper end of the stem is fixed a steering-wheel 21 for turning 75 the stem.

The wheel-stem 20, with its connecting-bar 19, and the rear ends of the link-bars, are supported from the body of the vehicle by the strap-bar 22, having the legs 23 diverging at 80 suitable equal angles from a central bearing portion 24, which is provided with a central orifice 25, through which extends the stem 20, on which is mounted the washer 26 above the bearing portion 24, upon which it rests, 85 and above the washer the stem 20 is provided with a diametric orifice through which is inserted a suitable cotter-pin 27, the ends of which rest upon the washer and with the washer forms a rotatable support for the stem 100 on the bearing 24. The legs 23 have portions 23' of their upper ends suitably angled and perforated for attachment to the bottom of the body of a vehicle transversely thereof, and thus attached by partially rotating the stem 105 in either direction by the wheel 21 one of the link-bars 18 is pushed forward and the other drawn an equal distance rearward by the con-

necting-bar 19, thereby turning the bolster 2 of the front axle 1 on its pivot-pin 10 and changing the angle of the axle to the body of the vehicle and the direction of the front 5 wheels.

Preferably the steering-gear described is also provided with a link-bar 28, which is suitably pivoted at one end centrally to the body portion 29 of the U-shaped strap 4 of 10 the bolster and at the opposite end to the stem 20 between the connecting-bar 19 and the bearing portion 24 of the strap-support 22. Said link-bar 28, by reason of its pivoted attachment to the stem and to the bolster 15 in line with the king-pin, forms a brace between the axle and the support 22, which prevents any leverage strain of the axle on the king-pin 10 (which it would otherwise be subject to by reason of the location of the axle 20 at a distance below the bolster-bearing) without in any degree effecting the free pivotal movement of the link-bars 18, the bolster 2, and the stem 20'.

While a wheel is preferably used as a means 25 of rotating the stem, it is apparent that any suitable lever or cross-handle may be substituted for the wheel.

A steering-gear constructed in accordance with my invention as described is strong and 30 durable and easily and conveniently operated, its parts are readily formed and assembled, and in complete form the whole is inexpensively and readily attached to vehicle-bodies of various construction. It is especially 35 adapted for use on that class of children's vehicles which are propelled by pedals adapted to revolve the rear wheels.

What I claim to be new is—

1. In a steering-gear for pedaled vehicles, 40 the combination with a body-support adapted to be secured to a vehicle-body, and having a centrally-disposed bearing, of a truss-bolster pivoted centrally of its length to the bearing of the support, said truss-bolster 45 comprising a central rectangular frame adapted at its top as a bearing for the support and lateral truss-bars extending oppositely and diverging downwardly at equal angles from the top portion of the central frame, said 50 truss-bars having end portions angled downward parallel with the sides of the central frame, an axle secured lengthwise of the bolster through the end portions of the truss-bars and through the sides of the central 55 frame, said axle having end journals for wheels projecting beyond the end portions of the truss-bars, link-bars pivotally connected

to the bolster, one on each side of its pivoted connection to the body-support, and extending rearwardly therefrom, a steering-bar pivotally connected at its ends to the rearward ends of the link-bars, an upward and rearwardly inclined stem having its lower end fixed centrally of and to the steering-bar, means to rotatably support the stem from and 60 extending upward through the body, and means secured to the upper end of the stem for rotating the stem in its support, substantially as set forth.

2. In a steering-gear for pedaled vehicles, 70 the combination with a body-support adapted to be secured to a vehicle-body, and having a centrally-disposed bearing, of a truss-bolster pivoted centrally of its length to the bearing of the support, said truss-bolster 75 comprising a central rectangular frame adapted at its top as a bearing for the support and lateral truss-bars extending oppositely and diverging downwardly at equal angles from the top portion of the central frame, said 80 truss-bars having end portions angled downward parallel with the sides of the central frame, an axle secured lengthwise of the bolster through the end portions of the truss-bars and through the sides of the central 85 frame, said axle having end journals for wheels projecting beyond the end portions of the truss-bars, link-bars pivotally connected to the bolster, one on each side of its pivoted connection to the body-support, and extended rearwardly therefrom, a steering-bar pivotally connected at its ends to the rearward ends of the link-bars, an upward and rearwardly inclined stem having its lower end fixed centrally of and to the steering-bar, 90 means to rotatably support the stem from and extending upward through the body, means secured to the upper end of the stem for rotating the stem in its support, and a link brace-bar pivotally connected at one 95 end to the bottom portion of the central frame of the bolster in line with the pivoted connection of the top bearing portion with the bearing of the body-support, and to the steering-stem at the opposite end, substantially as set forth.

In testimony whereof I have signed my name to this specification, in the presence of two subscribing witnesses, this 16th day of September, 1904.

GEORGE H. BARSCHOW.
